UNITED STATES PATENT OFFICE.

MARTIN J. QUINN, OF TORONTO, ONTARIO, CANADA.

ELECTRIC SWITCH.

1,271,221.

Specification of Letters Patent.

Patented July 2, 1918.

Application filed January 15, 1917. Serial No. 142,506.

To all whom it may concern:

Be it known that I, MARTIN JOSEPH QUINN, of the city of Toronto, in the county of York, Province of Ontario, and Dominion of Canada, have invented certain new and useful Improvements in Electric Switches; and I hereby declare that the following is a full, clear, and exact description of the same.

10 This invention relates to a combination switch for making and breaking an electric circuit, consisting essentially of an assemblage of relatively fixed and movable contacts, all of which, for the closing of the circuit, must be brought into series to effect the electrical connection by which the current may pass successively through each contact from one switch terminal to the other; one of the objects of the invention being, 15 to arrange these contacts in any preconcerted order so that they may be brought into series by the same or different degrees of movement; a further object of the invention being, to so arrange this assemblage 20 of contacts that any or all of them are capable of transposition, whereby the previous degree or degrees of movement may be altered to bring them into series.

For an understanding of the invention, 30 reference is to be had to the following description and to the accompanying drawings, in which—

Figure 1 is a front elevational view.

Fig. 2 is a rear elevational view.

35 Fig. 3 is a vertical section lengthwise of the switch, showing an open circuit therethrough.

Fig. 4 is a similar view to Fig. 3, showing the position of the moving contacts when 40 the circuit is closed.

Fig. 5 is a sectional plan of the construction shown in the preceding views.

Fig. 6 is a plan detail view on a larger scale than the preceding figures of one of the moving contacts, handle, and spindle shown in Figs. 2, 3, 4 and 5.

Fig. 6^a is an elevational detail view of the parts shown in Fig. 6, showing the inner dial for the spindle of the moving contact.

Fig. 7 is a detail view of a modification 50 of the moving contact shown in the preceding views.

Fig. 8 is a horizontal section of a modification of the construction of the switch shown in Figs. 1, 2, 3, and 4.

Like characters of reference refer to like parts throughout the specifications and drawings.

As shown in Figs. 1 to 5 inclusive, the switch case *a*, consisting of insulating material, is formed with three cylindrical receptacles *a'*, *a''*, *a³*, the circular walls of which are provided with axial grooves *b*.

Contained in the receptacles *a'*, *a''*, *a³* are independently moving contacts *c'*, *c''*, *c³*, respectively, always in pressure against the walls of the receptacles and during their rotation entering successively into the axial grooves *b*, whereby their movement may be sensible to the touch or hearing.

Each moving contact is connected by a spring *d* with a collar *d'* rotatable on its respective spindle *e'*, *e''* or *e³* journaled in the corresponding receptacle of the switch case; the collar being locked in its adjusted position on its spindle by a set screw *d''*. The spindles extend beyond the front of the switch case *a* and are provided with a rotating handle *f'*, *f''*, *f³* respectively, the inner end of each of which is of substantially the same diameter as that of its corresponding receptacle and forms therewith a revolving bearing for the outer end of its spindle.

On the outer side of the switch case *a* each handle is formed with an annular flange *f*, to conceal from view the positions of the fixed and movable contacts when the parts are assembled, and on the flange *f*, is a dial *f⁴* overlapping its receptacle, and the inner end of each handle being provided with a similar dial *f⁵*, with divisions corresponding in number and location with those of the dial *f⁴*, the purpose of the dial *f⁵* being to facilitate the transposition of the moving contacts, when a change of the "combination" on which they may be brought into series is desired.

On each handle is a raised indicator *g*.

opposite a predetermined division of its corresponding dial, so that the relative position of such division, in the cycle of rotation of the handle, with regard to the 5 zero mark g' on the switch case, can be ascertained in the dark.

The switch case a is provided with two binding posts h , h' extending into the switch case from beyond its rear face, each 10 binding post being provided with binding nuts h'' , by which the conductors may be connected thereto.

Within the switch case a , and in contact with the binding post h is a fixed contact i leading into the receptacle a' , to be engaged by the moving contact c' during its rotation. The spindle e' of the moving contact c' is 15 of conducting metal and extends beyond the rear face of the switch case a , and is electrically in circuit with the spindle e'' of the 20 moving contact c'' , by an electric connector j , consisting, as shown in Fig. 2, of a piece of spring metal, preferably copper, bored to fit on said spindles, and secured thereon in 25 tension by lock nuts k , so that the current may circuit from the binding post h , by means of the fixed contact i , moving contact c' and its respective spindle e' and connector j , to the spindle e'' of moving contact c'' .

In the switch case a is a fixed contact i' leading from the receptacle a'' to the receptacle a^3 whereby the current may circuit from the spindle e'' of the moving contact c'' to the moving contact c^3 and its respective spindle e^3 , the spindle e^3 of the moving contact c^3 being 35 similar to the spindles of the moving contacts c' , c'' , and in circuit with the binding post h' by an electrical connector j' , which 40 is also in tension and similar to the electrical connector j .

When the assemblage of moving and fixed contacts are in series, the circuit of the current through the switch is, by means of the 45 binding post h , fixed contact i , moving contact c' , spindle e' , electrical connector j , spindle e'' , moving contact c'' , fixed contact i' , moving contact c^3 , spindle e^3 and connector j' and binding post h' .

For the operation of the switch shown in the drawings, each dial consists of ten divisions numbered respectively from 0 to 9. If the fixed contact i is in line with the ninth 55 division of the dial when division 0 is opposite the zero mark and the moving contact c' is set opposite the 0 division of its respective dial, it will be necessary in bringing the moving contact into engagement with the fixed contact i , to rotate the handle nine-tenths of a complete revolution in a clockwise direction, or one-tenth of a complete revolution in the reverse direction.

Likewise, if the fixed contact i' is opposite the division 4 of the dial of the moving contact c'' when its division 0 is at zero, and opposite the seventh division of the dial of the moving contact c^3 when its division 0 is at zero, and the moving contacts c'' , c^3 are set opposite the divisions marked 65 0 of their respective dials, it will be necessary to rotate the moving contact c'' three-tenths of a revolution to bring it into engagement with the fixed contact i' , if moving in a clockwise direction, or seven-tenths 70 of a complete revolution, if moving in the reverse direction, and, it will be necessary to rotate the moving contact c^3 seven-tenths of a complete revolution, if moving in a clockwise direction, or three-tenths of a revolution 75 if moving in the reverse direction to bring it into engagement with the fixed contact i' .

Until the moving contact c' is in engagement with the fixed contact i and the moving contacts c'' , c^3 , are in engagement with the fixed contact i' , the circuit is open through the switch and the current cannot pass from the binding post h to the binding post h' . When they are in contact, as above 80 stated, all the electrical parts of the switch may be said to be in series and the current can freely circuit from one binding post to the other.

When the dials are visible, the moving contacts can be rotated into engagement with the fixed contacts, without regard either to the sensation of touch or hearing, resulting from their entrance into the axial grooves, but in the dark, it is advisable to 95 provide some means by which the rotation can be checked and the sensation resulting from the moving contacts entering these grooves, is found to be a satisfactory and convenient means for doing so.

In order to determine the relative positions of the moving to the fixed contacts, when the dials are not visible, the indicators g have been provided to permit of the rotating handles being first brought to the 100 zero position through the sense of touch, and from that position the distance traveled by the moving contacts in either clockwise or reverse direction may be easily determined by the sense of touch or sound as the 105 moving contacts pass the axial grooves.

The moving contacts can be set opposite any selected division of the dial to vary the combination upon which the circuit is closed, and the number of the moving and fixed contacts may be varied and so also may the 110 number of combinations which it is possible to make in bringing the moving contacts into engagement with the fixed contacts.

In Figs. 6 the moving contact is shown 125 to consist of a roller L , journaled in the

forks L' of the spring arm d , secured to the collar d' ; but in Fig. 7 the moving contact consists of a spoon shaped shoe m connected by an arm d to the collar on the spindle.

5 As it is possible, however, to use either of these types of contacts, or other modifications thereof, it is not desired to confine the invention to either or any of them.

The normal tendency of the spring arms 10 d is to hold the moving contacts with pressure against the walls of the receptacles and maintain the necessary "touch" between the fixed and moving contacts when in engagement.

15 In Fig. 8 the circuit of the current through the fixed and movable contacts is shown to be controlled by a combination of keys o , o' , o'' and o^3 , each of which carries a movable contact p , p' , p'' and p^3 respectively. In 20 this case eight fixed contacts numbered from 1 to 8 inclusive are employed, fixed contact 1 being provided with a binding post 9. Fixed contacts 2 and 3 are coupled by a connector 10, fixed contacts 4 and 5 are coupled by a connector 11, fixed contacts 6 and 7 are coupled by a connector 12, and fixed contact 8 is provided with a binding post 13.

The moving contacts p , p' , p'' , p^3 , are 25 provided with insulators q , q' , q'' , q^3 respectively. As shown in Fig. 8, the insulators q , q'' are located above the moving contacts and the insulators q' , q^3 are located below the moving contacts. In order to establish a connection through the switch it is 30 necessary to press inward the keys o , o'' and to press outward the keys o' , o^3 . This brings, the moving contact p into engagement with the fixed contacts 1 and 2, the moving contact p' into engagement with the 35 fixed contacts 3 and 4, the moving contact p'' into engagement with the fixed contacts 5 and 6, and the moving contact p^3 into engagement with the fixed contacts 7 and 8. The current then circuits through the switch 40 as follows: from the binding post 9 to the fixed contact 1, moving contact p , fixed contact 2, connector 10, fixed contact 3, moving contact p' , fixed contact 4, connector 11, fixed contact 5, moving contact p'' , fixed 45 contact 6, connector 12, fixed contact 7, moving contact p^3 , fixed contact 8, binding post 13.

If one of the keys, for instance o or o'' is 50 pressed outward instead of inward, the insulator q or q' will come into engagement with the fixed contacts, and the circuit will be immediately opened. The same result 55 would happen if either of the keys p' , p^3 were pressed inward, the insulators q' , q^3 then coming into engagement with the fixed 60 contacts would also result in the opening of the circuit. Thus, it is manifest that in order to close the circuit from the binding

post 9 to the binding post 13, it is necessary to operate the correct combination of keys. 65

Any number of keys with the corresponding fixed and movable contacts and insulators may be employed to increase or decrease the number of possible combinations which it may be desired to effect. 70

To hold the keys in their set position, that is to say, to either open or close the circuit through the switch, the inner ends of the keys o , o' , o'' and o^3 are provided with ball shaped protuberances r , to be engaged by 75 curved springs s , appropriately secured to the switch case a , which, as in the construction shown in other Figs. 1 to 5 inclusive, is of insulating material. It may be possible, however, to vary these springs and their attachment within the scope of the claims. 80

Other changes may be made in the construction of the switch, within the scope of the appended claims, without departing from the essential feature of the invention, 85 which is, to provide a switch with a combination of fixed and movable contacts, which must be brought into correct engagement before the circuit can be completed through the apparatus. It is also possible 90 to change the location of the fixed contacts within the switch case, so that the adjustment may be made in that way to effect a change of combination.

Having thus fully described my invention, 95 what I claim as new and desire to secure by Letters Patent is:—

1. An electric switch comprising a switch case of insulating material having a plurality of cylindrical receptacles, a rotatable contact in each receptacle, always in pressure against its cylindrical wall, and fixed contacts in the cylindrical walls of said receptacles arranged to be engaged by the rotatable contacts, one of said fixed contacts 100 extending through the walls of two of the receptacles, and conductors combined with the fixed and movable contacts completing the circuit through the switch. 105

2. An electric switch comprising a switch case of insulating material having a plurality of cylindrical receptacles, the walls of which are provided with axial grooves, a rotatable contact in each receptacle always in pressure against its cylindrical wall, and 110 fixed contacts in the cylindrical walls of said receptacles arranged to be engaged by the rotatable contacts, one of said fixed contacts extending through the walls of two of the receptacles, and conductors combined 115 with the fixed and movable contacts completing the circuit through the switch. 120

3. An electric switch comprising a switch case of insulating material having a plurality of cylindrical receptacles, a rotatable contact in each receptacle always in pres- 125

sure against its cylindrical wall, binding posts for the switch case and fixed contacts in the cylindrical walls of said receptacles arranged to be engaged by the rotatable contacts, one of said fixed contacts extending from one of the binding posts through the wall of one of the receptacles, and another of the fixed contacts extending through

the walls of two of the receptacles, and conductors combined with the movable contacts 10 and one of the binding posts.

Toronto, Ontario, January 9th, 1917.

MARTIN J. QUINN.
